ATTORNEY

UNITED STATES PATENT OFFICE

JAMES C. CAIRNCROSS, OF NASHUA, MONTANA

DOUBLE-ACTING PUMP

Application filed June 21, 1929. Serial No. 372,687.

This invention relates to a four-valve double acting pump, the general object of the invention being to provide a double acting pump which is of simple construction and the parts of which are readily accessible for repair and other purposes and one which may be used for deep wells and which may be used on a suction pipe having a drive point or sand point or an ordinary suction pipe.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawings wherein like characters denote like or corresponding parts throughout the several views, and in which:

Figure 1 is a longitudinal sectional view through the improved pump, the section being taken on the line 1—1 of Figure 2.

Figure 2 is a section on line 2—2 of Figure 1.

Figure 3 is a section on line 3—3 of Figure 1.

Figure 4 is a section on line 4—4 of Figure 1.

In these views, the numeral 1 indicates the cylinder member of the pump which is formed with the rings 2 at opposite sides thereof having the passages 3 and 3' therein, these passages being parallel to the cylinder 1'. A port 4 connects the lower end of the cylinder with the lower end of the passage 3 and a port 5 connects the upper end of the cylinder with the upper end of the passage 3', these ports being diagonally arranged, as shown. The upper and lower caps 6 are bolted to the ends of the cylinder member, as shown at 7, gaskets 8 being placed between the parts, and each cap is formed with a pair of sockets 9, the sockets of the lower cap extending into the threaded bore 10 of the cap, while the sockets of the upper cap open out through the inner face thereof. The lower end of each socket is threaded to receive the threaded valve seat 11 and a

spherical valve 12 rests on each seat. One of the valve seats of the upper cap has a diagonally arranged passage therethrough, as shown at 11'. The upper sockets communicate with the passages 3 and 3' and the lower sockets are connected with the lower ends of the passages by the passages 13 formed in the lower cap.

A piston 14 is arranged in the cylinder 1' and the rod 15 thereof passes through the upper cap and through a guiding tube 16 which has its lower end threaded in a socket 17 formed in the upper part of the cap. Lubricant retaining means 18 are placed in the lower part of the socket and surround a portion of the rod 15. A packing gland 19 is arranged at the upper end of the tube 16 through which the rod passes and the upper part of the tube is provided with a nipple 20 whereby lubricant can be forced into the tube to lubricate the rod and the inner walls of the tube, this lubricant reaching the means 18 in the socket 17.

A suction pipe 21 has its upper end threaded in the bore 10 and a discharge pipe 22 is threaded in the upper part of the upper cap 6.

From the foregoing it will be seen that on the up stroke of the piston 14, the suction created in the lower part of the cylinder will draw fluid from the suction pipe, past the valve 12 in the right hand socket 9 of the lower cap and through the passage 13, the lower part of the passage 3 and port 4 into said lower part of the cylinder and at the same time, the fluid in the upper part of the cylinder will be forced through the port 5 and the left hand socket of the top cap through the passage 13' into the discharge pipe 22. On the down stroke of the piston, a suction will be created in the passage 3' through the port 5 so that fluid will be drawn from the suction pipe into the passage 3' and this fluid will pass through the port 5 into the top part of the cylinder. The fluid in the lower part of the cylinder will be forced by the piston through the port 4, passage 3 and through the socket and its passage at the right hand side into the discharge port. Thus at each stroke of the piston, fluid

will be discharged from the cylinder and more fluid drawn into the cylinder.

As will be seen, this pump is very compact and simple and the parts are easily accessible for repair and other purposes. The parts can be lubricated from the top of the pump and the packing can be easily adjusted or repacked when necessary, and as the piston rod is thoroughly lubricated by the means shown, friction and wear are reduced to a minimum.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

A double acting pump comprising a cylinder having an axially located bore and longitudinal passages at opposite sides of the bore, heads fitted to the upper and lower ends of the cylinder and closing the upper and lower ends of the bore, each head having a hollow neck for the connection of a fluid conducting pipe, the upper head having sockets in its under side and upwardly and inwardly inclined passages communicating at their lower ends with the said sockets and at their upper ends with the neck, a valve seat in the lower end of each socket, a ball check valve resting on each seat, one of the valve seats communicating directly with the respective passage in the cylinder and the cylinder having a branch passage in its wall communicating with the other valve seat and with the upper end of the respective passage in the cylinder, the other valve seat of the upper head being provided with an inclined passageway substantially in alignment with the respective inclined passage in the upper head, the lower head having passages therein communicating at their upper ends with the lower ends of the respective passages in the cylinder and curved inwardly and communicating at their lower ends with the respective sockets in the lower head, and the cylinder having a passage in its lower end in communication with one side of the last mentioned passage in the cylinder.

In testimony whereof I affix my signature.

JAMES C. CAIRNCROSS.
